UNITED STATES PATENT OFFICE.

FRANK DE MINICO, OF NEW YORK, N. Y., ASSIGNOR TO POLLARD-ALLING MANUFACTURING COMPANY, OF NEW YORK, N. Y., A CORPORATION OF NEW YORK.

ADDRESSING-MACHINE.

1,104,170.

Specification of Letters Patent.

Patented July 21, 1914.

Application filed September 14, 1912. Serial No. 720,359.

To all whom it may concern:

Be it known that I, FRANK DE MINICO, a citizen of the United States, and a resident of New York, in the county of New York and State of New York, have invented certain new and useful Improvements in Addressing-Machines, of which the following is a specification.

This invention relates to addressing machines and particularly to that class thereof adapted for successively feeding to printing position a series of individual plates, taking impressions therefrom respectively and discharging the plates after using.

15 The object of my improvements is to provide a machine of the class specified, simple in construction and reliable in operation.

To these ends my improvements are illustrated in their preferred embodiment in the 20 accompanying drawings wherein—

Figure 1 is a side elevation, with the front leg removed, of my improved machine. Fig. 2 is a front elevation, and Fig. 3 is a plan corresponding therewith. Fig. 4 is a detail sectional elevation on line 4, 4 of Fig. 3, showing the parts in positions differing from the positions of Fig. 1. Fig. 5 is a sectional plan on line 5, 5 of Fig. 4. Fig. 6 is a sectional elevation on line 6, 6 of Fig. 30 4. Figs. 7, 8 and 9 are detail views illustrating the operation of my improvements. Fig. 10 is a detail view of one of the parts. Fig. 11 is a plan view, partly in section on line 1, 1 of Fig. 12, of a modified arrangement of some details of my improved machine; Fig. 12 is an elevation corresponding with the showing of Fig. 11, and Fig. 13 is a view similar to that of Fig. 12 but showing the parts in different positions.

40 My improved machine comprises printing bed 2 onto which the printing plates P are advanced, one by one, from a printing plate supply, or hopper 3. Slide 7, mounted for reciprocation on rod 40 parallel with printing bed 2, is provided with hook 8 pivotally mounted at 9 therein, and said hook is urged to its work by leaf spring 10, and heel 11 of said hook is stopped against the upper face of slide 7. Said hook is efficient for 45 engaging the rear end of the lowermost plate P, in hopper 3, and for advancing it over slideway 12 to printing bed 2. Printing platen 13 is adjustably mounted in the free front end of platen arm 14 and may be 50 reciprocated toward and away from print-

ing bed 2 by the oscillation of arm 14 on pivot 15 fixed in depending frame 16.

Main lever 17 is pivotally mounted on stud 18 in frame 16 and may be oscillated between stops 19 and 20 by hand or preferably by 55 foot power applied to the lower end thereof, not shown, but all according to well known practice. The upper end of lever 17, above pivot 18, is connected by link 21 to the overhanging rear end 22 of platen arm 14, 60 whereby, upon the oscillation of main lever 17, platen 13 is caused to move toward and from printing bed 2.

Turning freely on stud 23, fixed in hub 24 of frame 16, is plate lever 25, connected 65 at its upper end with plate slide 7 by link 26. Plate lever 25 is preferably composed of two members, hub portion 27 and arm portion 28. These members are pivotally connected at 29 and held in their normal, relative positions (of for instance Figs. 1 and 4) by spring 30. The object of this construction is to permit said lever 25 to collapse without breaking or damaging other parts of the machine. Said lever is constrained to 70 its rearward position, Fig. 4, by spring 31. Hub 27 has formed in the upper edge thereof tooth 32 for engagement by plate lever pawl 33 pivoted at 34 on main arm 17. When arm 17 is swung forwardly from the 75 position of Fig. 4 to that of Fig. 1, pawl 33 engages tooth 32 and swings plate lever 25 forwardly, thereby moving slide 7, and through hook 8, lowermost plate P from hopper 3 along slideway 12 a distance of 80 one plate length. Then by two more strokes of lever 17 successive plates are delivered into slideway 12 and the first plate is delivered to printing bed 2. Then at each successive swing of lever 17 a plate is delivered 85 into the slideway and the used plate is pushed out forwardly from off the printing bed.

In practice plates P will be inked upon reaching printing bed 2 but as means for so doing are well known in the art and form no part of my improvements further reference thereto is omitted.

As slide 7 is operated for advancing the plates by the forward swing of main lever 17, and as platen 13 is operated downwardly to print by the rearward swing of said lever, it will be obvious that the two operations are timed to suitably coact.

It will be observed that, as herein de- 110

scribed, at each swing of lever 17 and at each corresponding downward movement of platen 13, a plate is printed from, and afterward discharged. As well known in the art it is often desirable to make two successive impressions from each plate before discharging it, and at other times it is desirable to make three such impressions. For accomplishing these results I provide the following means: At each side of hub 27 of plate lever 25 and mounted for free rotation coaxially therewith are ratchets 36, 37 respectively, and pivoted at 34 on lever 17 at each side of and coaxially with pawl 33, are pawls 38, 39 for engagement respectively with said ratchets. The engaging points of pawls 38, 39 are wider than their respective ratchets and those points reach inwardly to partially overlap hub 27 for engagement, when permitted by their respective ratchets, with tooth 32 of that hub. For preventing the rotation of ratchets 36, 37, except when engaged by their respective pawls, I interpose frictional washers 42, 43 between said ratchets and fixed parts of the machine, as hub 24 and collar 41 respectively. Collar 41 is held against turning on stud 23 by pin 44. Washers 42, 43 and ratchets 36, 37 are held in frictional engagement respectively by spring 45.

Ratchet 37 is provided with six teeth, and alternate teeth 46, thereof, are of such depth as to permit pawl 39 to engage tooth 32 of hub 27, while the remaining teeth 47 of said ratchet are so shallow as to prevent the engagement of said tooth 32 by said pawl 39. Thus during alternate strokes of lever 17 and pawl 39, when that pawl is permitted to engage ratchet 37, lever 25 is actuated and a plate P is fed forwardly, and during the other alternate strokes of said lever 17 and pawl 39, lever 25 is not actuated but remains at rest while platen 13 descends to make a second impression from the plate then on the printing bed. This action is clearly illustrated in Figs. 7, 8 and 9. In Fig. 7 pawl 39 is in one of the deep teeth 46 and as that pawl moves forwardly to the position of Fig. 8, it engages tooth 32 of hub 27 and swings plate lever 25 from the position of Fig. 4 to that of Fig. 1. Pawl 39 then moving backwardly from the position of Fig. 8 engages one of teeth 47 and in its next forward movement travels idly with respect of tooth 32, see Fig. 9. Ratchet 36, Fig. 10, is provided with four shallow teeth 47 and two deep teeth 46 so arranged, that in coaction with pawl 38, platen 13 will descend three times for each plate P delivered thereunder.

For lifting and holding one or more of pawls 33, 38, 39 out of engaging positions with tooth 32 of hub 27 and ratchets 36, 37, I provide the following means: Between

hub 27 and lever 17 shaft 50 is rotatably mounted in hub 51 of frame 16. Said shaft is parallel with stud 23 and has fixed thereto adjacent to hub 27 lifting dog 52 in the vertical plane of and below pawl 38. Fixed to the outboard end of shaft 50 is dog 53. To the inner end of sleeve 54 turning freely on shaft 50 is secured lifting dog 55 in the vertical plane of and below pawl 33. Fixed to the outboard end of sleeve 54 is dog 56. To the inner end of sleeve 57 turning freely on sleeve 54 is lifting dog 58 in the vertical plane of and below pawl 39. Fixed to the outboard end of sleeve 57 is dog 59. Dogs 53, 56 and 59 are connected by links, as 60 to dog 58, with slide buttons, as 61 in table 35. Thus by sliding said buttons, as 61, forwardly to the position shown in Fig. 3, dogs 53 and 52 are swung in anti-clockwise direction to the positions shown in Figs. 1, 4 and 6 and pawl 38 is lifted and held out of engaging position with ratchet 36 and tooth 32. The other pawls may be similarly lifted as desired and at other times lowered into operative positions by a reverse movement of their governing buttons respectively. Thus by lifting pawls 38 and 39 and leaving pawl 33 in operative position, each stroke of main lever 17 will present a fresh plate to the printing bed. By lifting pawls 33 and 38 and leaving pawl 39 in operative position, only alternate strokes of lever 17 will present a fresh plate to the printing bed. By lifting pawls 33 and 39 and leaving pawl 38 in operative position only every third stroke of lever 17 will present a fresh plate to the printing bed. Also, by lifting all of pawls 33, 38 and 39, lever 17 will operate without affecting the plate feed at all, and the printing will be continuously repeated from whatever plate is on the printing bed.

In Figs. 11, 12 and 13 I have illustrated a modified arrangement of the mechanism for actuating plate lever 25 from main lever 17. In this modification I employ only one pawl 110 as 33, pivoted to lever 17 at 34, for engagement with tooth 32 of hub 27. Also for spring 31 for returning lever 25, I substitute link 71 having one end slotted for sliding engagement with pivot 34 of main lever 17, and the other end slotted for sliding engagement with pin 63 in the upreaching portion of hub 27. Said link 71 is provided with pin 64, between which pin and pin 63, spring 62 is stretched for urging link 71 in the direction of said pin 63. In the modification of Figs. 11, 12 and 13 ratchets 36, 37 are fixed to shaft 50 and on that portion of that shaft behind frame 16, friction washers 42, 43 are mounted on opposite sides of collar 65. To said collar 65 is pivoted arm or lever 66 for moving shaft 50 and the parts mounted thereon endwise to bring ratchets 36, 37, small collar 67 and large collar 68 in operative position, one at a time 130

as needed, with tooth or nose 69 of pawl 33. Small collar 67 is efficient when in line with pawl 33, for permitting that pawl to engage at every forward stroke of lever 17, tooth 5 32 of hub 27; and large collar 68 is efficient under like circumstances for preventing the engagement of said pawl and tooth.

I claim:

1. An addressing machine including in combination, a printing bed, a reciprocating platen, a printing plate supply, means for successively advancing plates from the supply to the printing bed, a main lever, a pivoted plate lever operatively connected to 10 said plate advancing means, means pivotally connected to said main lever for oscillating said plate lever and settable means interposed between said plate lever and plate lever oscillating means for governing the 15 oscillations of said plate lever.

2. An addressing machine including in combination, a printing bed, a reciprocating platen, a printing plate supply, means for successively advancing plates from the supply to the printing bed, a main lever, means for reciprocating said platen from the main lever, a pivoted plate lever operatively connected to said plate advancing means, said plate lever having a pawl-engaging tooth 25 and a plate lever pawl pivoted on said main lever for engagement with said plate lever tooth.

3. In an addressing machine, the following parts in combination: a printing plate supply, reciprocating means for successively advancing plates from said supply, a main lever, a pivoted plate lever operatively connected to said reciprocating plate advancing means, means for oscillating said plate lever 30 from the main lever and settable means interposed between said plate lever and plate lever oscillating means for governing the oscillations of said plate lever.

4. In an addressing machine, the following parts in combination: a printing plate supply, reciprocating means for successively advancing plates from said supply, a main lever, a pivoted plate lever operatively connected to said reciprocating plate advancing 45 means, said plate lever having a pawl-engaging tooth and a plate lever pawl pivoted on said main lever for engagement with said plate lever tooth.

5. In an addressing machine, the following parts in combination: a printing plate supply, means for successively advancing plates from said supply, a main lever, a pivoted plate lever operatively connected to said plate advancing means, means for oscillating the plate lever from the main lever including a plurality of pivotally mounted ratchets each effective, when selected, for at one time permitting the plate lever oscillating means to oscillate the plate 55 lever and at another time for preventing

said means from oscillating the plate lever, and other means for, at another time, continuously permitting said oscillation, and hand operated means for making said selection.

6. In an addressing machine, the following parts in combination; a printing plate supply, means for successively advancing plates from said supply, a main lever, a pivoted plate lever operatively connected to 70 said plate advancing means, means on said main lever for oscillating said plate lever, a plurality of pivotally mounted ratchets each operable, when selected, for at one time rendering said plate lever oscillating means 75 ineffective and at another time for rendering said plate lever oscillating means effective, and hand operated means for making said selection.

7. In an addressing machine, the following parts in combination: a printing plate supply, reciprocating means for successively advancing plates from said supply, a main lever, a pivoted plate lever operatively connected to said reciprocating plate advancing means, a plate lever pawl pivoted on said main lever for oscillating said plate lever, a plurality of pivotally mounted ratchets each actuated, when selected, by said plate lever pawl and each operable, when so selected, 95 for at one time holding said pawl out of coaction with said plate lever and at another time for permitting coaction of said pawl with said plate lever, hand operated means 90 for changing the relation of said ratchets and plate lever pawl respectively, and frictional means for holding said ratchets 100 against rotation.

8. In an addressing machine, the following parts in combination: a printing plate supply, reciprocating means for successively advancing plates from said supply, a main lever, a pivoted plate lever operatively connected to said reciprocating plate advancing means, a plate lever pawl pivoted on said 105 main lever for oscillating said plate lever, a plurality of pivotally mounted members each actuated, when selected, by said plate lever pawl and each operable, when so selected, for at one time holding said pawl out of coaction with said plate lever and at another time for permitting coaction of said pawl with said plate lever or for continuously holding said pawl out of coaction with said plate lever or for continuously 110 permitting coaction of said pawl with said plate lever, and hand operated means for 115 making said selection.

9. In an addressing machine, the following parts in combination: a printing plate supply, reciprocating means for successively advancing plates from said supply, a main lever, a pivoted plate lever operatively connected to said reciprocating plate advancing means, a yieldable connection between 125 120

said plate lever and said plate advancing means, a plate lever pawl pivoted on said main lever for oscillating said plate lever, a plurality of pivotally mounted ratchets each actuated, when selected, by said plate lever pawl and each operable, when so selected, for at one time holding said pawl out of coaction with said plate lever and at another time for permitting coaction of said

pawl with said plate lever, and hand operated means for making said selection.

Signed at New York, N. Y., this 12th day of September, 1912, before two subscribing witnesses.

FRANK DE MINICO.
